UNITED STATES PATENT OFFICE.

JAMES G. DARLING, OF NORWOOD, OHIO.

CUTTING-BLADE ATTACHMENT.

Application filed August 19, 1925. Serial No. 51,208.

My invention relates to cutting blade attachments of the type set forth in Patent No. 1,359,339, granted William A. Darling, November 16, 1920.

5 The object of the present invention is to provide a simple, efficient, durable, and inexpensive cutting blade attachment which is adapted to be readily and conveniently detachably secured to claw-hammer heads 10 of varying sizes and shapes without any extraneous fastening means and to be readily detached therefrom, when desired.

The invention consists in providing a blade similar in shape to a hatchet blade 15 but recessed or dished at its back and having a curved widened bearing part and having spaced-apart holding pins whereby the claws of the hammer will bear against said curved part and between said spaced-apart pins and whereby said cutting blade is 20 adapted to be securely held in operative position upon claw-hammer heads of varying sizes and shapes.

My invention also consists in the peculiar 25 construction, combination, and arrangement of parts, as set forth and claimed.

In the drawings:

Fig. 1 is a side view of the cutting blade attachment embodying my invention, applied in operative position to a hammer head;

Fig. 2 is a section taken on the line 2—2 of Fig. 1, looking in the direction of the arrows;

Fig. 3 is an isometric view of the cutting blade attachment;

Fig. 4 shows the manner of sliding the back of the blade into the slot between the claws of the hammer and of sliding the claws of the hammer between the spaced-apart pins to the position shown in Fig. 5;

Fig. 5 is a view showing it sliding into wedging engagement with the claws of the hammer and blade while giving it a slight tap whereby it is firmly wedged and held upon the hammer claws;

Fig. 6 shows the blade detached and its manner of use as a chisel;

Fig. 7 shows the method of removal or 50 detachment of the blade from the hammer claws;

Fig. 8 shows the attachment on the hammer while it is being used for pounding;

Fig. 9 shows its use for heavy cutting 55 strokes; and

Fig. 10 shows its use as a hand blade for light slivering or shaving.

In the embodiment of my invention, as illustrated, and which shows a preferred construction, I provide cutting blade attachment 1 of substantially the shape shown in Figs. 1, 2 and 3, with spaced-apart blade holding pins 2 and 3, as indicated in said figures. The back of said blade is provided with a curved widened bearing 4, depression 5, and striking head 6. Said blade is also provided with the usual sharp cutting edge 7. I have found by experience that claw hammers for use of carpenters and others, are made of the same general shape but vary considerably in size and contour whereby it becomes necessary to provide supplementary fastening means which is adapted to compensate for such variations as well as any inequalities in the formation of hammer heads of the same make. For this purpose I have provided the spaced apart holding pins 2 and 3, so placed that claws of varying curves and sizes are adapted to be inserted and wedged therebetween with the curved back of the claws bearing against the curved widened bearing 4, so that when the hammer head 8 is pounded upon any object it forces and wedges the claws of the hammer between said spaced-apart pins and tightly against said bearing 4, whereby it is securely held in position thereon either while using said hammer head or while using the cutting edge of the blade. It will also be noted that the back edge of the blade between bearing 4 and striking head 6 is very thin in order to permit it to enter a very narrow slot, such as 10, between the claws 11 and 12, thereby providing further for variation in construction of different claw hammers.

It will be further seen that I provide a cutting blade attachment having a recessed back with a curved bearing upon one side of said recessed back and a pair of spaced-apart pins arranged one above the other and projecting to each side of said blade attachment at the other side of said recessed back; and that their opposed faces make line contact with the inner and outer faces of the claws, so that a three-point contact is made with the pair of claws on each side of the blade.

An advantage of this construction is that the holding pins will not only permit claws

of varying shapes and sizes to be wedged therebetween but there is no danger of their breaking off or permitting the blade to become loose while in use. This construction permits of the formation of a striking head whereby the cutting blade may be readily used as a chisel for a cutting operation such as is illustrated in Fig. 6, or it may be effectually used as a hand blade as shown in Fig. 10. When the cutting blade is securely mounted in position, as shown in Fig. 1, in the manner above set forth, the implement is ready to be used either to perform the ordinary functions of a hammer or hatchet, as desired, and then when it is desired to use either the hammer claws separately for their customary functions, or to use the cutting blade separately, as in Figs. 6 or 10, said cutting blade can readily be detached in the manner illustrated in Fig. 7. Thus I have provided a combination implement whereby the use of a hatchet and also the use of a chisel are dispensed with, and accordingly a great saving is effected in cost to the user and also he is enabled to carry this attachment in his pocket, ready for instant use in all emergency or other cases.

Some of the advantages of this invention are that it converts the regular claw hammers into hatchets; enables the user to get into tight places or small places inaccessible to the regular hatchet; may be used as a hatchet, a chisel, or a handblade for cutting or slivering; securely holds itself in place without screws, bolts, or other separate parts, and automatically locks itself to the hammer; can be carried in the pocket or under the belt; eliminates the need of carrying a hatchet; and occupies but little space in the tool kit. It is so simple in its construction that it slides into interlocking engagement automatically with the claws of the hammer without the use of screws, bolts, or other separate parts and there is nothing to get out of order. When it is once held in the claws of the hammer it remains secure for delivering the heaviest of cutting strokes. Hard blows on the hammer cannot loosen the blade but simply serve to wedge it more tightly to the hammer. It is as easy to remove or detach as it is to apply or put in place on the hammer. The blade cannot interfere with the use of the hammer for hammering purposes and if you desire to add weight to the hammer in delivering heavy blows, leave the blade in position, as it will not work loose. In practice, the blade is carried in the pocket and is readily accessible at all times. The hammer is usually carried in the workman's hand or is close by and whenever any cutting or chopping is

necessary no time is lost in searching for the hatchet.

The principal advantage of this invention over prior structures of this kind is its adaptability to hammers of varying sizes and shapes.

The holding pin 2 is secured somewhat nearer to bearing 4 than pin 3 in order that when the claws 11 and 12 of the hammer are forced between said pins and against said bearing, it will form a wedging and gripping action of the bearing and pin 3 on one side and of pin 2 on the other side of the claws 11 and 12, respectively, as clearly shown in Fig. 1.

My invention is capable of some modification without departure from its scope or spirit as defined in the claims:

What I claim as new and desire to secure by Letters Patent is:

1. A cutting blade attachment having spaced-apart pins adapted to receive the claws of a hammer therebetween and a bearing against which the convex surface of said claws is adapted to abut, whereby said cutting blade is adapted to be securely and detachably held in position upon said hammer.

2. A cutting blade attachment having a recessed back with a curved bearing upon one side of said recessed back and a pair of spaced-apart pins arranged one above the other and projecting to each side of said blade attachment at the other side of said recessed back, and their opposed faces making line contact with the inner and outer faces of the claws, so that a three-point contact is made with the pair of claws on each side of the blade, substantially as and for the purposes set forth.

3. A cutting blade attachment comprising a body having a cutting edge, a recessed back having a thin central edge with a bearing on one side thereof and with cooperating spaced-apart holding pins projecting from each side of said body and a striking head on the other side thereof, all substantially as and for the purposes set forth.

4. A hammer having tapering claws spaced apart by a tapering nail extractor slot, in combination with a cutting blade attachment comprising a body having a sharp edge with a recessed back having a thin edge adapted to be inserted in said slot and having a bearing adapted to engage said hammer and spaced-apart pins adapted to receive therebetween the tapering claws whereby said blade is adapted to be mounted on and detachably secured to hammers of varying sizes and shapes.

JAMES G. DARLING.
